UNITED STATES PATENT OFFICE

ISAAC GRODSKY, OF BROOKLYN, NEW YORK

SHOE POLISHING OUTFIT

Application filed May 16, 1930. Serial No. 452,848.

My present invention relates to a portable shoe polishing outfit in which the essential parts, the brush, the dauber, the polisher and the box of shoe paste are assembled together into one convenient article ready at any time for immediate use. The combined article thus presented is of compact form, capable of ready disassociation when required for use and may be conveniently carried in a traveling bag without soiling the other articles therein.

One of the objects of the present invention is to provide a shoe polishing outfit which is simple in structure and arrangement, inexpensive to manufacture, and durable and practical in use. Another object of the present invention is to provide a simple and complete device of this character incorporating coacting means for holding a box of shoe paste, means for applying the shoe paste to shoes, and means for polishing the shoes after the paste has been applied thereto. A still further object of the present invention is to provide a device of this character having a removable and replaceable polisher and having a body provided with openings in which the box of shoe paste and brush are detachably retained. Other objects and advantages of the present invention will in part be pointed out in detail hereinafter and will in part be apparent to those skilled in the art to which the present invention relates and to those who shine their own shoes.

With the above and other objects in view, my invention consists of the novel construction, combination and arrangement of parts more specifically described hereinafter, and illustrated in the accompanying drawing, wherein is shown an embodiment of my present invention. It is, however, to be understood, that my present invention is not limited to the specific embodiment thereof herein described and illustrated in the drawing.

I shall now describe an illustrative embodiment of my present invention, reference being had to the accompanying drawing forming a part of this specification, wherein like reference characters indicate corresponding parts throughout the several views.

Fig. 1 represents a top view of a preferred embodiment of the present invention;

Fig. 2 represents a longitudinal sectional view thereof on line 2—2;

Fig. 3 represents a top view of the present invention with the brush removed; and

Fig. 4 represents a fragmentary perspective view of the polishing member of the present invention.

Referring now to the drawing wherein I have illustrated an embodiment of my present invention it will be seen that the shoe polishing outfit consists of a body 10 which is constructed of wood, metal or other suitable material.

Positioned at one end of the body 10 is an opening 11 adapted to receive a box of shoe polish 12 and to removably retain the same. Toward the other end, the body 10 is provided with an opening 13 adapted to receive the bristles 14 of a brush 15. The brush 15 comprises a back 15' a handle 15" and a bristle section 14. The portion of the body 10 provided for receiving the box of shoe polish 12 is reduced in thickness equal to the thickness of the brush handle 15" and is adapted to engage the brush handle 15". The opening 13 is provided with a marginal limiting projection 16 which engages the brush back 15' and frictionally retains the bristles 14 within the opening 13. The brush handle 15" is provided with a shallow recess 17 on its under side which is normally disposed with reference to the opening 11 and acts as a cover for the box of shoe polish 12 inserted within the opening 11.

Removably attached to the under side of the body 10 is a polishing member 18. Referring to Figs. 2 and 4 it will be seen that the polishing member 18 consists of a metal plate 19 running longitudinally with the body 10 and having its ends 20 rolled over as indicated at 20' to form a pair of jaws 21 which engage the body 10 by cooperating with grooves 22 at the end portions of the body 10. Secured to the under surface of the plate 19 is a compressible pad or cushion 23 preferably of soft rubber. Covering the face of the cushion 23 is a polishing strip 24 of cloth, felt or other suitable material. The polishing strip 24

extends over the entire face of the cushion 23, over the rolled ends 20 of the plate 19, and is attached to the upper surface of the plate 19. This arrangement permits the polishing strip 24 to be removed and replaced in the event 5 that it wears out.

In Fig. 4 I have shown a preferred method of securing the cushion 23 to the under surface of the plate 19 and for attaching the 10 polishing strip 24 to the upper surface of the plate 19. The cushion 23 is provided with hooks 25 on the surface of the cushion 23 adjacent to the under surface of the plate 19. The hooks 25 are spaced from the ends of the 15 cushion 23 and are adapted to engage the plate 19 through the holes 26 which are similarly spaced from the ends of the plate 19. The extremities of the polishing strip 24 are provided with hooks 27 which also engage 20 the plate 19 through the holes 26. Other means than that above described may be employed to produce the same effect.

The manner of use of my present invention is apparently simple. When one desires to 25 polish his shoes with the shoe polishing outfit, he simply holds it in one hand and removes the brush 15 by gripping the latter at the handle 15" with the other hand. The shoe polish box 12 is also uncovered with this 30 same operation and is ready for the end portion of the bristles 14 to be introduced therein and the blacking applied to the shoes. To dry the blacking on the shoes requires merely a little rubbing with the brush 15. The brush 35 15 is then returned to its original confines and the entire assembled article is taken in hand and the shoes are given a polish by means of the polishing member 18. Obviously one does not require to touch the polish box with 40 his hands during the entire process.

When the polishing strip 24 wears out, the 45 polishing member 18 is removed by pulling at the jaws 21 of the plate 19, and the polishing strip is removed and replaced by another. The polishing member 18 is then snapped back into place, the jaws 21 engaging the 50 grooves 22. The effect of snapping the polishing member 18 onto the body 10 is to stretch the polishing cloth 24, thus securing a smooth polishing surface.

It will also be apparent that the device is 55 constructed to give a maximum of efficiency and economy. The brush when not in use is completely retained within the body of the outfit thereby eliminating the danger of its contact with other articles which are likely to be soiled. The polishing cloth is removably attached to the outfit and is replaceable when worn out, while the brush handle performs the 60 additional function of a cover for the box of polish.

Although the preferred embodiment of my 65 invention is as illustrated and described, yet I desire it understood that changes in the details of construction can be had which will

fall within the scope of the invention as claimed.

What I claim is:

A shoe polisher comprising in combination with an elongated rectangular rigid body having transverse grooves in its ends, of a resilient pad, a plate of spring metal on the upper surface of said pad, said plate having apertures near its ends and raised inturned beads at its end edges to engage the grooves in said body, hooks having heads set in said pad to extend through the plate apertures thereby to bind the plate to said pad, a textile polishing strip covering the lower surface and ends of said pad, said strip extending over the plate beads, and hooks fixed in the ends of said strips to engage in the plate apertures, whereby when the beads are forced into the grooves of said body they draw the strip taut. 70 75 80

In witness whereof, I have signed my name 85 to this specification this 15 day of May, 1930.

ISAAC GRODSKY.
